W. J. NELSON.
HOISTING APPARATUS.
APPLICATION FILED JAN. 17, 1921.

1,412,956.

Patented Apr. 18, 1922.

Inventor;

William J. Nelson

Attorney

Horace Barnes,

UNITED STATES PATENT OFFICE.

WILLIAM J. NELSON, OF CENTRALIA, WASHINGTON.

HOISTING APPARATUS.

1,412,956.

Specification of Letters Patent. Patented Apr. 18, 1922.

Application filed January 17, 1921. Serial No. 437,681.

To all whom it may concern:

Be it known that I, WILLIAM J. NELSON, a citizen of the United States, residing at Centralia, in the county of Lewis and State 5 of Washington, having invented certain new and useful Improvements in Hoisting Apparatus, do hereby declare that the following is a full, clear, and exact description of the same.

10 This invention relates to improvements in hoisting apparatus for actuating cableways used in logging or for other analogous purposes.

The invention has for one of its objects 15 the provision of hoisting apparatus of simple construction whereon a plurality of cables may be wound and unwound either separately or simultaneously, whereby a load may be raised, transported and deposited with facility and economy in construction, operation and power.

A further object of the invention is the provision of hoisting apparatus whereby a load may be hoisted to clear the ground obstructions and may then be held at such elevation without substantial additional power being required to maintain the load in its elevated position or during its transportation.

30 The invention resides in the novel construction and adaptation of a power hoist arranged and provided to handle a logging cableway, as well as for general use as a hoist, as will be fully described in the following specification, illustrated in the accompanying drawings, and finally set forth in the appended claims.

In said drawings, wherein like parts are 40 designated by similar reference characters throughout the several views, Figure 1 is a pictorial view in side elevation of a cableway system and hoisting apparatus embodying my invention.

Fig. 2 is a plan view of said hoisting apparatus, partly broken away, to show certain portions in section.

Fig. 3 is a view in side elevation of the same, parts being broken away.

Referring to Fig. 1, the reference numeral 50 10 indicates the head-spar or spar-tree supporting one end of the apparatus and 11 indicates the tail-spar supporting the opposite end thereof. 12 designates guy-lines arranged in any desired or suitable manner. 55 Numeral 13 indicates generally the hoist, to be hereinafter more particularly described,

from the drum 15 of which the supporting line 16 of the cableway extends through the upper sheave-block 17 which is secured to the spar-tree 10 and thence the line 16 passes 60 to the tail-spar 11 where it passes through block 18 and thence returns as the so-called haul-back line 20 to the dependent member 21 of the carriage 22 where its end is secured. A haul-in line 23 extends from the 65 drum 25 of the hoist 13 through block 26 on spar 10 and thence to the member 21 where its end is secured. Said carriage 22 is of the usual trolley-carriage construction, consisting in parallel plates with grooved traction 70 wheels 22' rotatably mounted between the plates and adapted to run on the supporting line 16 in a well understood manner.

Referring to Figs. 2 and 3, illustrating my cable or log hoisting apparatus, the 75 drum 15 carrying the supporting-line 16 of the cableway is mounted rigidly on arbor 27. Said arbor is provided with loosely mounted gear wheels 28 and 30 on opposite sides of said drum 15, which gear wheels are provided with friction clutches 31 and 31', respectively, operative to engage with drum 15 to actuate the latter in either rotary direction when either of said friction clutches is set against the drum by well known or suitable shifting devices 32 and 33, respectively, either of the manually operated type or by steam actuated devices, an operating lever being shown at 34.

The drum 25 of the same diameter as 90 drum 15 is loosely mounted on arbor 35 and the gear wheels 36 and 37 on opposite sides of the drum are rigidly mounted or keyed on the arbor. Said drum 25 is shifted to engage friction clutch devices 41 on the gear 95 36 to actuate the drum 25 in the direction indicated by the arrow on gear 36.

The drive pinion 42 mounted on power-shaft 43 and driven through power-crank 43' is in constant mesh with the gear wheels 100 28 and 37 and the gear wheels 30 and 36 of corresponding size on the arbors 27 and 35, respectively, are in mesh with each other. Both said drums 15 and 25 are provided with brake devices and operative mechanism, not shown, in the usual manner.

To hoist a load, represented by 47, the drum 25 carrying the haul-in line may be held stationary, as by the brake, and the supporting line 16 on the drum 15 is hauled in by maintaining the clutch device 31' in its disengaged position and engaging the friction

clutch 31 with the drum 15. The motive power is then transmitted from power-pinion 42 to gear wheel 28 which is actuated in the direction of the arrow on said gear wheel 5 to haul in on line 16, which hoists the load into the air to any desired height.

To convey the load toward the hoist the drums 15 and 25 are actuated in opposite directions which is accomplished by setting 10 the friction clutch 41 to rotate the drum 25 in the direction indicated by the arrow on gear 36 and setting the friction clutch 31' to operate drum 15 in a contrary direction to that of drum 25, or as indicated by the arrow 15 on gear 30. The gears 36 and 30 being in mesh and with the friction clutches 41 and 31 engaged with their respective drums the load may be held in the air by the interlocking of the said gears through their tendency 20 to rotate in opposite directions.

To return the carriage to pick up another load the drum 25 is allowed to unwind the cable 23 through what tension there may be exerted thereon by the brake devices associated with said drum 25 and by releasing the friction clutch 41 while the friction clutch 31 is engaged with gear 28 to cause the drum 15 to rotate in the direction of the arrow on gear 28.

30 A power drum 48 is also provided similar in most respects with drum 15 being rigidly mounted on its arbor. Said drum is provided with gear wheels 51 and 52 on opposite sides of said drum 48, respectively, which 35 are in mesh with the respective gear wheels 28 and 30 and are likewise arranged with friction clutches 53 and 55, respectively, and clutch-actuating devices similar to those described and shown. Power on said drum 48 40 is applied through pinion 42 and intermediate gears 28 or 30, as the case may be, in a manner that will be well understood. The purpose of drum 48 is to provide an extra power driven drum which may be used for 45 any purpose desired and which may also be utilized to operate in connection with drum 15 in case loads are to be transported along the cableway in both directions. In the latter event the line 16 may be shifted to drum 48 and line 23 to drum 15.

Having described my invention, what I claim is—

1. In hoisting and conveying apparatus, an arbor, a hoisting drum rigidly mounted 55 on said arbor, a gear wheel loosely mounted on each side of said drum and arranged to be frictionally engaged with said drum, a second arbor, a hoisting drum rotatively mounted on said second arbor, a gear wheel 60 keyed to said second named arbor on each side of said rotative drum, one of which gear wheels is frictionally engageable to the rotative drum, and a drive pinion operatively engaged with a gear wheel on one end of

each of said arbors, the gear wheels on the 65 opposite ends of the arbors being in mesh.

2. In hoisting and conveying apparatus, an arbor having a winding drum rigidly mounted thereon, a second arbor having a winding drum loosely mounted thereon, a gear wheel 70 loosely mounted on said first named arbor adapted to be frictionally engaged with said rigidly mounted drum, a gear wheel keyed to said second named arbor, a power pinion in mesh with both said 75 gear wheels, and a loose and a keyed gear wheel on the ends of said arbors opposite to said pinion-driven gear wheels, respectively, in mesh with each other and each adapted to be frictionally engaged with 80 their respective winding drums.

3. In hoisting and conveying apparatus, an arbor, a winding drum rigidly mounted thereon, a second arbor, a winding drum loosely mounted thereon, a gear wheel loosely 85 mounted on said first named arbor at each end of said rigidly mounted drum and each arranged to be frictionally engaged with said drum, a gear wheel keyed to said second named arbor, a power driven pinion in mesh 90 with said last named gear wheel and with one of said first named gear wheels, and a gear wheel keyed to the second named arbor and in mesh with the other of said first named gear wheels and provided with releasable 95 clutch devices to actuate said loosely mounted drum.

4. In hoisting and conveying apparatus, an arbor, a winding drum rigidly mounted thereon, a second arbor, a winding drum 100 loosely mounted thereon, a gear wheel loosely mounted on said first named arbor at each end of said rigid drum and each arranged to be frictionally engaged with said drum, a gear wheel keyed to said second named arbor, a power driven pinion in mesh with said 105 last named gear wheel and with one of said first named gear wheels, a gear wheel keyed to the second named arbor and in mesh with the other of said first named gear wheels and provided with releasable 110 clutch devices to actuate said loosely mounted drum, a third winding drum rigidly mounted on an arbor, and loosely mounted gear wheels on opposite ends of said third drum in mesh with the 115 gear wheels, respectively, on said first named arbor, and each arranged to be frictionally engaged with said third drum.

5. In hoisting and conveying apparatus, an arbor having a drum rigid thereon, a 120 loose gear on each end of said arbor, a second arbor having a loose drum and a rigid gear in mesh with one of said loose gears, and power actuated means to drive said rigid gear and the other loose gear in the 125 same direction.

6. In hoisting and conveying apparatus, an arbor, a hoisting drum rigidly mounted

on said arbor, a gear wheel loosely mounted on each side of said drum and arranged to be frictionally engaged with said drum, a second arbor, a hoisting drum rotatively mounted on said second arbor, a gear wheel keyed to said second named arbor frictionally engageable with said second named drum, and in mesh with one of said loosely mounted gear wheels, and power actuated means to drive said keyed gear-wheel and the other of said loosely mounted gear-wheels in the same direction.

5. In hoisting and conveying apparatus, an arbor having a winding drum rigidly

10 mounted thereon, a second arbor having a 15 winding drum loosely mounted thereon, gear wheels loosely mounted on said first named arbor on opposite sides of said rigid drum and frictionally engageable thereto, a gear wheel rigidly mounted on said second arbor frictionally engageable with the loosely mounted drum and in mesh with one of said loose gear wheels, and power means to drive said loose gear wheels in opposite directions.
